COLLAPSIBLE CORE

Walter H. Cobi, New York, N. Y.

Application October 30, 1937, Serial No. 171,867

20 Claims. (Cl. 25—128)

This invention relates to collapsible and expandable cores, especially those adapted for use in molds for cementitious materials, and has for its object to provide a simple and inexpensive 5 device of this class which is easy to insert and remove from the cast material after it has at least partially set.

Another object is to provide such a core which is adapted to be self collapsing when the expanding stress has been removed.

A further object is to provide means for limiting both the amount of expansibility and the extent to which the core may be collapsible.

Still another object is to provide a flexible, 15 water impervious envelope around said core which is adapted to keep water from flowing into the core.

Referring to the drawing—

Fig. 1 is a longitudinal view mostly in section 20 through one embodiment of this invention.

Fig. 2 is a section on the line 2—2 of Fig. 1 showing the core in expanded position.

Fig. 3 is a view corresponding to Fig. 2 but with the core in collapsed position.

Fig. 4 shows another embodiment of this invention.

Side members 10, 11, 12 and 13 may be of any size or shape desired in order to give the desired configuration to the core. Ply wood, press wood 30 or aluminum has been found a desirable material for use in constructing these side members or blocks. When the core is polygonal in cross section there may be as many side members as desired, that is, three or more. Arranged within 35 in these side members 10 to 13 is a means 14 for expanding the side members, which in the embodiment illustrated includes a rubber cylinder 14 adapted to be expansible and compressible. A heavy gum rubber has been found suitable for 40 this purpose.

Surrounding the cylinder 14 is a means 15 for 45 limiting expansibility of the cylinder 14 and comprising a tube of thin spring brass or its equivalent about .005 to .01 inch in thickness. Between the metal cylinder 15 and the side blocks 10 to 13 are arranged spacing blocks 16, 17, 18 and 19 which contact with the expansive means 50 for pressing the side members outwardly.

Surrounding the core is a flexible water-im- 55 pervious envelope 20 which is adapted to prevent water from flowing into the core from the wet cementitious material. This envelope comprises a canvas covering 21 preferably of sail cloth which is rugged yet adapted to be stretched and the ends of the canvas may be turned in adja-

cent the stitching 22 which limits the approximate size of the canvas part of the envelope. Surrounding the canvas 21 is a waterproof paper 23 which may be loose and just have its ends overlapped without being adhesively secured. 5

The canvas may if desired be waterproofed and the paper eliminated. The paper may also have its lapped edges held together by a waterproof adhesive to form an envelope of the right 10 size. Neither the paper nor the canvas is permanently secured to the side members.

Within the core are arranged at spaced intervals a number of very strong rubber bands 24 or other springy material capable of being stressed sufficiently to automatically collapse the 15 core when desired. These rubber bands 24 are about $\frac{3}{4}$ of an inch wide by about $\frac{1}{4}$ of an inch thick and are longitudinally spaced apart about 5 inches. Each of these bands 24 is held in place by the heads on the inner ends of pins 20 25, 26, 27 and 28, the outer ends of these pins being perforated to receive the supporting pins 29, 30, 31 and 32. The rubber is substantially stressed in tension at all times so that the pins 25 to 28 inclusive are likewise in tension. The supporting pins 29 to 32 inclusive 25 are each arranged in recesses 33 in the side blocks and the rubber bands 24 are arranged between longitudinal portions of the blocks 16 to 30 19 inclusive.

End plugs 34 and 35 of rubber or other appropriate material are vulcanized to the end portions of the rubber cylinder 14 and in addition the ends of the rubber cylinder may be bound around these plugs by stressed hooks or wrapped 35 wire. Passing axially through the cylinder 14 is a tension rod 36, the ends of which are secured to the plugs and this rod 36 prevents the cylinder 14 from elongating longitudinally an objectionable amount. 40

One end portion of the rod 36 is bifurcated at 37 for attachment to the flanged end of an air supply tube 38, which is preferably valved as is the air supply valve to an ordinary inner tube. The ends of the mold, not shown in the drawing, 45 are preferably located between or within the ends of the collapsible core so that the core may project through the end walls of the mold. The rubber bands 24 each is stressed to take about forty pounds pressure when the core is expanded 50 as in Fig. 2 and when the core is collapsed as shown in Fig. 3 these bands are still under tension.

The metal sleeve or cylinder 15 limits the 55 expansibility of the rubber cylinder 14 and there-

fore the amount to which the core may be expanded when air pressure is applied within the rubber cylinder 14. When the cylinder 14 is deflated its walls may still serve to limit the amount of contractibility to which the core may be moved or, if desired, the ends of each side member are preferably beveled as illustrated so that when the core is collapsed the side members are brought into contact with one another and thus the beveled edges of the side members may constitute a means for limiting the degree to which the core may be collapsed.

When the core is collapsed the rubber bands 24 are still preferably under tension a less amount, say twenty pounds or less. The rubber bands 24 cause each of the side members to be moved radially inward with respect to the rubber cylinder substantially the same amount.

When the metal cylinder 15 is collapsed it is in the form of substantially a square as shown in Fig. 3 with the corners rounded in order that flexure of the metal which takes place mostly at the corners may not be too greatly stressed in a small area as would be the case if the corners or edges were sharper. If the metal 20 15 cannot be purchased on the market in tubular form already preshaped, then it may be necessary to make this metal of the desired shape. To accomplish this purpose sheet brass may be rolled 25 into cylindrical form with the edges lapped and soldered.

In order to localize flexure at approximately the corners these corners or edges may be given a permanent set by insertion of a mandrel whose 30 edges are rounded to the desired amount and the brass then ironed or rolled over the edges of this mandrel to give it a permanent set so that when the rubber cylinder is collapsed the metal cylinder will take the rectangular or square form 35 illustrated in Fig. 3 when the mold has four sides.

To assemble the core shown in Figs. 1 to 3 the sleeve 15 is placed over the rubber cylinder 14. The rubber bands 24 are next arranged longitudinally over the metal and rubber cylinders 15 40 and 14. The headed pins 25 to 28 inclusive are next placed in position by lifting up a portion of the rubber band and inserting each pin through the pre-formed perforation.

With these pins radially projecting from the 45 rubber bands the side members 10 to 13 inclusive and their spacing blocks 16 to 19 inclusive may next be placed in position around the metal and rubber cylinder with the rubber bands and their pins arranged in spaces provided between the 50 blocks 16 to 19 and through the perforations provided in the side members. By taking a pair of sharp pointed pliers or other convenient tool each headed pin may be raised radially outward a sufficient amount to enable its supporting 55 pin to be passed through the perforate end. When the supporting pins 29 to 32 inclusive are in position the core is then in collapsed condition ready to receive the fibrous or other water impervious envelope which may be slid over the 60 collapsed core. The paper and canvas may together be placed on the core as a unit.

When ready for use the core is expanded and placed in the mold with the ends of the core projecting through the walls of the mold. After 65 the concrete or other cementitious material has at least partially set enough to retain its form and allow withdrawal of the core, air may be let off from the pressure cylinder 14 in the same way that air is let out of an automobile tire, 70 causing the rubber cylinder 14 to collapse or be-

come of reduced diameter as shown in Fig. 3 and collapsing the metal sleeve 15 causing the side members to be moved radially inward until their edges are contiguous, under the influence of the rubber bands 24.

The side members together with the contained metal and rubber cylinders may then be removed after being collapsed, leaving the canvas and paper in place. After the side members have been removed the canvas and paper will be found 10 to be very easily detachable from the cementitious material, though of course if the paper were allowed to stay in place until the concrete has more completely set it might be held tightly.

In Fig. 4 is shown another embodiment of this 15 invention which has been described in my prior copending application Serial Number 115,729 filed December 14, 1936, for Hollow cementitious slab and its process of manufacture, of which this case is a continuation in part. The collapsible core of Fig. 4 includes side members 40, 41, 42 and 43 arranged around the rubber tube which is similar to that shown in Fig. 1 except that the side members directly contact with the rubber tube 44. The tube 44 is bent out of its 20 cylindrical shape by its contact with the side members. Of course there is a longitudinal tension rod through the rubber cylinder 44, for the 25 same purpose as mentioned above in connection with Fig. 1.

On the outer surface of each side member is secured a metal plate 45 and bridging adjacent metal plates is a much thinner flexible sheet 46 which may be soldered in place. The thin flexible strips 46 limit expansibility of the core in 30 Fig. 4. When collapsed upon removal of air pressure the rubber cylinder 44 returns to a substantially cylindrical shape thus enabling the side members to be moved radially inward flexing or 35 bowing the metal portions 46 enough to permit 40 removal of the core.

As shown in dotted lines in Fig. 4 the rubber cylinder 44 when deflated returns to its substantially cylindrical shape illustrated. In Fig. 4 the rubber cylinder is what limits the amount or 45 degree to which the core may be collapsed. In event the metal shell of the core does not readily become disconnected from the partially set concrete, it may be released by driving wedges 50 into the mold between the concrete and the core.

Among the advantages of this invention may be mentioned the provision of rubber bands or other stressed means for positively collapsing the core. The embodiment illustrated in Fig. 4 may, if desired, have a paper envelope around it in 55 order to facilitate removal of the core. The water impervious fibrous envelope has little or no tendency to stick to the partially set concrete. The provision of a metal envelope which is under tension serves as a convenient limit for the 60 amount of expansibility of the core. The provision of some appropriate means to limit the degree to which the core may be collapsed is another advantageous feature.

An especially noteworthy feature of the invention shown in Figs. 1 to 3 is the metal cylinder or sleeve 15 which changes its shape from the cylindrical cross section shown in Fig. 2 to the substantially square or rectangular shape shown 65 in Fig. 3.

I claim:

1. An expandable and collapsible core including metallic means for limiting the expansibility of the core, means for expanding said core, resilient means opposing the said expanding means 70

and tending to collapse said core, and means for limiting the degree to which said core may be collapsed.

2. An expandible and collapsible core including metallic means for limiting the expansibility of the core and means for limiting the degree to which said core may be collapsed, a fluid pressure means for expanding said core and means opposing said fluid pressure means and tending to collapse said core.

3. An expandible and collapsible core including a longitudinal fluid pressure cylinder which is radially expandible and contractible, angularly spaced substantially rigid blocks around the outside of said cylinder and adapted to be moved radially outward by expansion of said cylinder, and means comprised in said core for limiting the outward movement of said blocks and expansion of said cylinder.

4. An expandible and collapsible core including a longitudinal fluid pressure cylinder which is radially expandible and contractible, angularly spaced substantially rigid blocks around the outside of said cylinder and adapted to be moved radially outward by expansion of said cylinder, and means comprised in said core for limiting the outward movement of said blocks and expansion of said cylinder, said cylinder being of rubber and having a longitudinal tension rod extending through said cylinder for limiting longitudinal expansion thereof.

5. An expandible and collapsible core including a longitudinal fluid pressure cylinder which is radially expandible and contractible, angularly spaced substantially rigid blocks around the outside of said cylinder and adapted to be moved radially outward by expansion of said cylinder, and means comprised in said core for limiting the outward movement of said blocks and expansion of said cylinder, and a water impervious layer extending around the outside of said blocks and angularly between them forming an envelope for said blocks and cylinder, at least a portion of said layer being flexible enough to allow said envelope to expand.

6. An expandible and collapsible core including a longitudinal fluid pressure cylinder which is radially expandible and contractible, angularly spaced substantially rigid blocks around the outside of said cylinder and adapted to be moved radially outward by expansion of said cylinder, and means comprised in said core for limiting the outward movement of said blocks and expansion of said cylinder, said expansion limiting means including a metal tube enclosing said cylinder and at least portions of which are flexible enough to bend when said blocks and cylinder are contracted to remove said core from a mold.

7. An expandible and collapsible core including a longitudinal fluid pressure cylinder which is radially expandible and contractible, angularly spaced substantially rigid blocks around the outside of said cylinder and adapted to be moved radially outward by expansion of said cylinder, and means comprised in said core for limiting the outward movement of said blocks and expansion of said cylinder, the adjacent sides of said blocks being bevelled to contact on radial inward movement of said blocks and cylinder whereby the engagement of one block with one on each side thereof may limit the contraction of said core on removal of pressure from said cylinder.

8. An expandible and collapsible core including a longitudinal fluid pressure cylinder which is radially expandible and contractible, angularly

spaced substantially rigid blocks around the outside of said cylinder and adapted to be moved radially outward by expansion of said cylinder, and means comprised in said core for limiting the outward movement of said blocks and expansion of said cylinder, said expansion limiting means including a metal tube enclosing said cylinder and at least portions of which are flexible enough to bend when said blocks and cylinder are contracted to remove said core from a mold, the bending of portions of said metal tube occurring along a line longitudinally thereof.

9. An expandible core comprising angularly spaced blocks cooperating with an expandible means and forming open spaces between them when expanded, a canvas like envelope surrounding said blocks and bridging the open spaces separating the blocks when expanded and a waterproof coating on said envelope, whereby said core is adapted for use with wet cementitious material to be molded.

10. A collapsible core including a metal tube, means for applying pressure inside said tube and stressing the same by tension into a substantially circular shape, means for relieving pressure within said tube and moving portions of the tube walls radially inward to a substantially polygonal cross section with rounded corners whereby said tube may be repeatedly expanded and collapsed.

11. An expandible and collapsible core including a longitudinal fluid pressure cylinder which is radially expandible and contractible, angularly spaced substantially rigid blocks around the outside of said cylinder and adapted to be moved radially outward by expansion of said cylinder, and means comprised in said core for limiting the outward movement of said blocks and expansion of said cylinder, said cylinder being of rubber and having a longitudinal tension rod extending through said cylinder for limiting longitudinal expansion thereof, at least a portion of said tension rod having a valved passage for the supply and exhaust of compressed air.

12. A collapsible core including an expandible fluid pressure chamber, a flexible metal envelope around said chamber for limiting expansion thereof, blocks angularly spaced around said metal envelope, and a fibrous water impervious envelope around said blocks.

13. A collapsible core including an expandible fluid pressure chamber, a flexible metal envelope around said chamber for limiting expansion thereof, blocks angularly spaced around said metal envelope, and a fibrous water impervious envelope around said blocks and tensioned means connecting said blocks outside said metal envelope and tending to move said blocks radially inward.

14. A collapsible core including an expandible fluid pressure chamber, a flexible metal envelope around said chamber for limiting expansion thereof, blocks angularly spaced around said metal envelope, and a fibrous water impervious envelope around said blocks and tensioned means connecting said blocks outside said metal envelope and tending to move said blocks radially inward, said tensioned means comprising longitudinally spaced rubber bands surrounding said metal envelope and secured to said blocks.

15. A collapsible core including an expandible fluid pressure chamber, a flexible metal envelope around said chamber for limiting expansion thereof, blocks angularly spaced around said metal envelope, and a fibrous water impervious envelope around said blocks and tensioned means

- connecting said blocks outside said metal envelope and tending to move said blocks radially inward, said tensioned means comprising longitudinally spaced rubber bands surrounding said metal envelope and secured to said blocks, said blocks also being spaced longitudinally and said bands being located longitudinally between said blocks, radially between said metal and fibrous envelopes, and being hung from supports bridging the space between adjacent blocks.
16. An expandable and collapsible core including metallic means for limiting the expansibility of the core and means for limiting the degree to which the core may be collapsed, means for expanding said core, and means opposing said expanding means and at least partially collapsing said metallic means and also at least partially collapsing said second mentioned means.
17. An expandable and collapsible core including metallic means for limiting the expansibility of the core, means for limiting the degree to which the core may be collapsed, means for expanding said core, elastic means opposing said core expanding means and adapted to effect at least a partial collapse of said metallic means and of said second mentioned means.
18. A collapsible core including angularly spaced substantially rigid blocks, means radially within and between said blocks for moving them substantially radially inward and outward, and

a water impervious envelope around said blocks adapted at least in part to be stretched by the blocks in moving outward and strong enough alone to support wet cementitious material across the space between each pair of blocks.

19. A collapsible core including angularly spaced substantially rigid blocks, means within and between said blocks for moving them substantially radially outward, means also within and between said blocks for moving them substantially radially inward, and a water impervious envelope around said blocks adapted at least in part to be stretched by the blocks in moving outward and strong enough alone to support wet cementitious material across the space between each pair of blocks.

20. The combination with an expandable fluid pressure container, of a metallic tube surrounding and contiguous said container for limiting expansion of the container, a water impervious tube outside the first mentioned tube, blocks spacing the first and second mentioned tubes, and resilient means cooperating with said blocks and adapted on release of fluid pressure to collapse said container and move said blocks toward each other for removal of said blocks, resilient means, metallic tube and container from said water impervious tube.

WALTER H. COBI. 30
